WITNESSES

ATTORNEY

UNITED STATES PATENT OFFICE.

WARREN FRANK LIVINGSTON, OF NEW BOSTON, ILLINOIS.

COOP.

Application filed August 28, 1922. Serial No. 584,804.

To all whom it may concern:

Be it known that I, WARREN FRANK LIVINGSTON, a citizen of the United States, residing at New Boston, in the county of 5 Mercer and State of Illinois, have invented new and useful Improvements in Coops, of which the following is a specification.

My present invention has reference to improvements in poultry coops.

10 In carrying out my invention it is my purpose to produce a coop in which the sliding door or gate will cooperate with the remainder of the coop in a manner to hold the same in closed position without the employment of locking or latching means.

15 The foregoing, and other objects which will present themselves as the nature of the invention is better understood, may be accomplished by a construction, combination 20 and operative association of parts such as is disclosed by the drawing which accompanies and which forms part of this application.

In the drawing:—

25 Figure 1 is a perspective view of a coop in accordance with this invention.

Figure 2 is an approximately central vertical longitudinal sectional view therethrough.

30 Figure 3 is a substantially similar view but showing the manner in which the door is moved to open position.

Fig. 4 is a perspective view illustrating a detail.

35 The body of the coop 1 is of the ordinary slatted construction. On the inner face of the ends of the coop, at the center thereof I secure uprights 2 respectively. These uprights terminate a slight but suitable distance from the top 3 of the coop, and at the 40 top thereof I secure one or more transverse members 4. When two members are employed, I notch their confronting ends at the center thereof and when a single element is employed I provide the same with a central 45 opening. The upper wall of the opening, indicated by the numeral 5, is disposed a slight distance above the upper edges of the uprights 2, and the slats that form the top 3 of the coop are arranged longitudinally 50 thereof, and the inner slats are spaced a distance away equalling or exceeding the length of the opening 5.

Through the opening 5 I slide the board

that provides the door 6. As the lower wall provided by the opening 6 is disposed below the upper edges of the uprights 2, and as the board is of a length equalling the length of the coop between the uprights, the said door will be slightly swayed toward the center thereof. The ends of the door 6 are in contact with the ends 7 of the coop, and thus it will be noted that the door may be effectively sustained in closed position without the employment of auxiliary fastening means.

65 The door, at the ends thereof is provided with finger holes 8, and in sliding the door to open position the operator inserts his fingers through the holes adjacent one of the ends of the door and springs the said door upwardly above the edge of the ends of the coop so that the door can be slid through the opening 5. The opposite end of the door is sprung when the door is inserted through the opening and is brought to closed 70 position.

75 It is thought that the foregoing description, when taken in connection with the drawing will fully set forth the construction, operation, simplicity and advantages of 80 the improvement and that further detailed description will not be required.

Having described the invention, I claim:

1. A poultry coop having a central longitudinal opening in the top thereof, a member arranged transversely of the coop at the center thereof and provided with a central opening, and uprights at the ends of the coop terminating a slight distance above the lower wall of the opening, and a door comprising a yieldable board designed to be slid through the opening and to rest on the uprights.

90 2. A poultry coop having a central longitudinal opening in the top thereof, a member arranged transversely of the coop at the center thereof and provided with a central opening, and uprights at the ends of the coop terminating a slight distance above the lower wall of the opening, and a door comprising a yieldable board designed to be 95 slid through the opening and to rest on the uprights, and finger holes in the door adjacent to the ends thereof.

100 In testimony whereof I affix my signature.

WARREN FRANK LIVINGSTON.
